UNITED STATES PATENT OFFICE.

BICK R. BONNEY, OF OMAHA, NEBRASKA, ASSIGNOR OF FORTY ONE-HUNDREDTHS TO
V. F. HOFMAN AND FIFTEEN ONE-HUNDREDTHS TO C. O. JOHNSON, BOTH OF HAVE-
LOCK, NEBRASKA.

ROAD-GRADING MACHINE.

1,255,285.

Specification of Letters Patent.

Patented Feb. 5, 1918.

Application filed December 14, 1916. Serial No. 136,996.

To all whom it may concern:

Be it known that I, BICK R. BONNEY, a citizen of the United States, residing at Omaha, in the county of Douglas and State 5 of Nebraska, have invented certain new and useful Improvements in Road-Grading Machines, of which the following is a specification.

This invention relates to an improvement 10 in road graders, and has for its object to provide a machine by use of which the rough or uneven surfaces of highways may be made smooth, or for use in forming new roads which are convexed in cross-section, 15 the structural parts to be few and so arranged that they will be convenient in use and may be economically manufactured. The invention includes the combination with a vehicle of a plurality of blades mounted 20 thereon and disposed inclinedly to the longitudinal axis thereof and at different distances from its front, so that the excavated earth may be conveyed transversely of the vehicle while moving forwardly, toward the 25 middle of the road, means being provided to change the inclination of the blades, transversely of the vehicle, as may be required. Also the invention includes means for throwing a furrow inwardly of a roadway at 30 the gutter or sides of a roadway, this being quite necessary where sods or turf are encountered.

With the foregoing objects in view and others to be hereinafter mentioned, the invention 35 presents a novel construction, combination and arrangement of parts as described herein and claimed, and as illustrated in the accompanying drawing, wherein,—

Figure 1 is a plan view of the machine, 40 and Fig. 2 is a view of the same in side elevation. Fig. 3 is a section on line 3 3 of Fig. 4. Fig. 4 is a broken away plan view showing an adjusting plate and its connection with the inclined cross-bar of the vehicle frame. Fig. 5 is a detail showing a plan view of the sod-cutter.

Referring now to the drawing for a more particular description, I provide a vehicle frame of any suitable construction, but preferably having parallel side bars or plates 6

and 7, and a suitable number of inner frame plates disposed parallel therewith, as indicated at 8, 9 and 10, and a front cross-bar 11 disposed inclinedly with reference thereto, angle iron preferably being used for these parts, a rear axle 12 being provided which may have bearings in the rear ends of the parallel frame plates or may be secured thereto, as desired; and the rear wheels 13, preferably, are arranged to rotate 60 on the axle.

Extending forwardly from the frame thus described and connected with the cross-bar 11 is a secondary frame for the comparatively short front axle 14, the wheels 15 rotatable thereon having a limited diameter as compared with the rear wheels, said axle and the tongue 16 being adapted to swing while connected by a king bolt 17 with the plate 18, disposed in line with the longitudinal axis of the vehicle and supported by the pair of bars 19, inclined stay rods 20 and 21 being employed for supporting this secondary frame.

It will be understood that the provision 75 of the inclined cross-bar and its connections thus described is for convenience when "turning about" for a reverse direction of movement of the vehicle, since the machine is for excavating and removing the earth 80 from the sides to the middle of a roadway, and on account of the construction, the machine may be turned for moving in a reverse direction upon an area less than ordinary.

At 22 are indicated a plurality of scraper 85 blades normally disposed parallel with reference to each other and inclined with reference to the axis or line of travel of the vehicle. Any suitable means may be provided for pressing these blades into the ground, 90 the means herein shown for this purpose being pockets or receptacles 23, one of these receptacles being secured upon and at the rear side of each blade for containing a weight, such as rock or earth, each blade 95 also being inclined forwardly and downwardly, for the same purpose.

Each blade is provided with a tongue or "goose-neck," consisting of a pair of arms or rods 24 and 24', the arms 24 having a less 100

length than the arms 24', and each pair of arms being connected with one of the blades and extending convergently in a forward direction for a mounting upon a tie-plate 25, the tie-plates being connected with the cross-bar 11 at longitudinal intervals thereof by means of staples arranged in pairs as indicated at 26 and 27, means being provided for changing the inclination of each arm 24 10 and each scraper blade since the staples 27 may be mounted as shown in Fig. 4 or may engage in one of the apertures 28 and 29 formed in the tie plates and in the arms 24 which, in operation, would result in less resistance or stresses being directed to the blades.

It will be understood that the blades will engage in the ground when the machine moves forwardly, and that the dislodged or 20 excavated earth will, on account of the inclination mentioned for the blades, be conveyed transversely of the machine substantially from the side bar 7 to somewhat beyond the side bar 6, said blades being of 25 sufficient length so that a part of each rearward blade will be disposed in the plane and at the rear of a part of a blade disposed forwardly thereof, the result being that the ground scraped or operated upon will have 30 a smooth surface, the flanges on the vehicle wheels tending to resist side stresses. Also it will be understood that a greater or lesser degree of flexibility is provided by reason of the employment of a plurality of blades 35 as compared with a single long blade, since the particular mounting provided by the tie-plates and staples permit the blades to enter the ground independently of each other, which tends to form a roadway convexed in 40 cross-section.

Numeral 30 indicates a plow-member for forming a furrow or channel below the side rail 7 in which the rear wheel, adjacent to said side rail, may engage, for disposing the 45 vehicle frame inclinedly transversely of the roadway and for other purposes, said plow-member preferably consisting of an arm 31 pivotally mounted at 32 upon a hanger 33 which is secured upon the front end of the 50 side bar 7, the rear end of arm 31 providing bearings for a shaft or wrist pin 34 upon which are mounted the pair of disks 35, said disks being disposed inclined to the line of travel of the machine in a manner to throw 55 the furrows inwardly of the machine at the front of the foremost blade.

The member 30 thus described is quite necessary in the operation of the machine for several reasons. Where sods are 60 encountered they must be cut and a channel or gutter must be formed at the sides of a highway since the roadway is to be convexed in cross-section, said channel also permitting the foremost blade to readily enter the

ground, as well as providing a depression 65 for receiving one of the rear wheels to cause the vehicle frame to be disposed inclinedly as mentioned.

Numeral 36 indicates a weighted arm for causing the disks 35 to enter the ground and the weight 37 may be adjusted longitudinally of the arm 36, its bolt 38 being adapted to engage in any one of the apertures 39, for regulating the downward pressure upon the disks. Any suitable means may be provided 70 for elevating the blades and disks, as the cables or strands 40, 41, 42, 43 and 44 engaging suitable pulleys and under control of levers 45 and 46, this being necessary when 75 "turning about" for a reverse movement of 80 the machine, or when driving the machine from one location to another.

Having fully described my invention, what I claim and desire to secure by Letters Patent is,—

1. In combination with a frame having substantially parallel side plates and a cross-bar disposed at an oblique angle to and connected with the side plates, said frame being provided with front and rear wheels, 90 tie-plates disposed at longitudinal intervals of and connected with the cross-bar, a plurality of scraper blades, a plurality of tongue-members each consisting of a pair of arms of unequal length mounted upon and 95 adjacent to the ends of a scraper blade and extending forwardly convergently for a mounting upon a tie-plate for disposing a scraper blade inclined to the longitudinal axis of the frame, an earth-working member 100 including a weighted arm pivotally mounted upon a side plate and provided with axially mounted disks disposed at the front of one of said scraper blades in line with one of the rear wheels, means for elevating 105 said earth-working member and scraper blades with reference to the frame, and means on the tie-plates connected with the cross-bar for adjusting the degree of inclination of the scraper blades transversely of 110 said frame.

2. In combination with a frame having substantially parallel side plates and a cross-bar connected with the side plates, said frame being provided with front and rear 115 wheels, tie-plates disposed at longitudinal intervals of and connected with the cross-bar, a plurality of scraper blades, a plurality of tongue-members each consisting of a pair of arms of unequal length mounted upon 120 and adjacent to the ends of a scraper-blade and extending forwardly convergently for a mounting upon a tie-plate for maintaining the scraper-blades at intervals longitudinally of and inclined with reference to the side plates, an earth-working member including a weighted arm pivotally mounted 125 upon a side plate and provided with axially

mounted disks disposed at the front of one of said scraper-blades in line with one of the rear wheels, means for elevating said earth-working member and scraper-blades with reference to said frame and means for adjusting the scraper-blades transversely of the frame.

In testimony whereof I have affixed my signature in presence of two witnesses.

BICK R. BONNEY.
